EXTRUDED STRUCTURAL ELEMENT FOR BUILDINGS

Lindell N. Edwards, St. Louis, Mo., assignor to
Universal Modular Structures, Inc., St. Louis, Mo.

Filed Feb. 14, 1972, Ser. No. 226,377

Term of patent 14 years

Int. Cl. D25—01

U.S. Cl. D13—1 H

FIG. 2.

FIG. 3.

FIG. 1 is a perspective view of the upper end of an extruded structural element for buildings which embodies my new and ornamental design,

FIG. 2 is an elevational view of the upper end of that side of the extruded structural element for buildings which faces downwardly and to the right in FIG. 1, and which faces downwardly and to the left is a mirror image of that side, and

FIG. 3 is a sectional view, on an enlarged scale, through the extruded structural element for buildings shown in FIG. 1, and it is taken along the plane indicated by the line 3—3 in FIG. 2.

The extruded structural element for buildings is broken away at the lower end thereof in FIGS. 1 and 2 to indicate indeterminate length.

I claim:
The ornamental design for an extruded structural element for buildings, as shown and described.
